Primary Examiner—Wallace R. Burke*Assistant Examiner*—Robin V. Taylor*Attorney, Agent, or Firm*—Myron B. Kapustij; Malcolm L. Sutherland[57] **CLAIM**

The ornamental design for a shower head, as shown and described.

DESCRIPTION

FIG. 1 is a perspective view of a shower head showing my new design;

FIG. 2 is a bottom plan view thereof;

FIG. 3 is a top plan view thereof; and,

FIG. 4 is a side elevational view thereof, the opposite side being identical.

The broken line drawing of the connection at the base of the shower head is shown for illustrative purposes only and forms no part of the claimed design.
